UNITED STATES PATENT OFFICE.

BESSIE E. HAYNES, OF WASHINGTON, DISTRICT OF COLUMBIA.

HAIR WAVER.

Application filed October 29, 1926. Serial No. 144,999.

The invention relates to new and useful improvements in hair wavers, and more particularly to a hair waver which is adapted to form the so-called water wave.

5 An object of the invention is to provide a hair waver of the above type wherein a bar is passed through a slotted base portion for bending or crimping the hair to form a wave, and wherein said bar, after the wave is 10 formed, can be moved laterally of the base portion so as to produce an inclined or irregular wave in the hair.

A further object of the invention is to provide a hair waver of the above type, 15 wherein the bar crimping the hair to form the wave may be moved to either side of the base, and therefore, the wave in the hair may be caused to incline away from the crown of the head.

20 A still further object of the invention is to provide a hair waver of the above type wherein the base portion is provided with means for frictionally holding the bar in its laterally shifted position, thus doing away 25 with any latches which might become entangled with the hair.

These and other objects will in part be obvious and will in part be hereinafter more fully disclosed.

30 In the drawings which show by way of illustration one embodiment of the invention—

Figure 1 is a plan view of a hair waver embodying my improvements, and showing 35 in broken lines the crimping bar in its lateral shifted positions;

Fig. 2 is a side view of the waver;

Fig. 3 is a diagrammatic view showing the 40 waver as applied to the hair, and with the crimping bar as forced through the base portion so as to form a wave in the hair;

Fig. 4 is a similar view, but showing the bar as moved to the left as viewed in this figure, for producing an inclined or irregular 45 wave;

Fig. 5 is a view similar to Fig. 4, but showing the bar as moved to the right, and the wave inclined in the opposite direction from that in Fig. 4, and

50 Fig. 6 is a diagrammatic view showing a series of wavers applied to the hair at one side of the crown, thus forming a series of waves.

The invention is directed broadly to a hair waver which includes a base portion having 55 a slot extending longitudinally thereof, and a crimping bar which is adapted to be moved through said slot for bending or crimping the hair to form a wave therein. The bar is preferably pivoted at one end to the base 60 portion of the waver, and shoulders are provided on the side portions of the main part of the waver between which the free end of the bar may be forced or snapped, and these shoulders will hold the bar frictionally from 65

returning and releasing the hair. The base portion of the waver is preferably provided with a looped part at each end, so that the side members are relatively close together, and so that said bar may be moved in said 70 looped portions laterally in either direction, so as to be positioned entirely at one side of the side members.

The purpose of laterally shifting the bar is to increase the length of the wave, and also for the purpose of forming a slanting or irregular wave, wherein the distance from the base of the wave to the crest at one side, is longer than at the other. The base portion of the hair waver is provided with shoulders over which the bar 80 is snapped or forced when moved laterally, and these shoulders serve to hold the bar in its laterally shifted position.

Referring more in detail to the drawings, my improved waver consists of a base portion having side members 1 and 2. These side members are joined at one end by a loop 3, wherein the portion 4 thereof extends substantially at right angles to the longitudinal axis of the waver. These side members 1 and 90

2 are connected at the other end by the loop portion 5. This loop portion 5 is bent upwardly, and the part 6 thereof is curved intermediate its ends. Pivotal connected to the part 4 of the loop 3 is a crimping bar 7. 95

This bar 7 is provided with an enlarged head 8, which is perforated so as to receive the part 4 of the loop 3. This forms a pivotal support for the bar 7, and a pivotal support along which the bar can slide 100 from the full line position in Fig. 1, to the broken line position indicated at 7', or to the broken line position indicated at 7''.

The loop 5 is shaped so that the bar 7 which projects beyond this looped part and 105 is located therein, can be shifted laterally as

just described. The members 1 and 2 are gradually tapered toward each other at the free end of the bar, and these side members 1 and 2 are provided with shoulders 8 and 9. 5 The shoulders 8 and 9 are spaced so that the bar 7 can be forced up between the shoulders, the parts yielding to allow the bar to pass. These shoulders provide a frictional holding means for preventing the bar from passing 10 out of the loop 5. The shoulders 8 and 9 are also raised relative to the body portion of the waver as shown in Fig. 2. The side member 1 is provided with a shoulder 10 at the other end thereof, while the side member 15 2 is provided with a shoulder 11 at its other end. These shoulders are raised as shown in Fig. 2. The purpose of these shoulders 8, 9, 10 and 11 is to serve as a holding means for holding the bar in its laterally shifted positions. The side members 1 and 2 are curved to conform to the head of the wearer, and the bar 7 is also similarly curved. These curvatures, however, are 20 slightly different, so that the shoulders lie in the path of movement of the bar 7. The parts carrying the shoulders will spring to permit the bar to pass over the shoulders.

In the operation of my device, a strand of hair is placed over the bar 7 before it is 30 moved through the slot between the side members 1 and 2. It is then forced through the slot, and this bends or crimps the hair as shown in Fig. 3, where the strand of hair is indicated at H. After the bar has been 35 forced through the slot as indicated in Fig. 3, it is then moved laterally to the left as indicated in Fig. 4, or to the right, as indicated in Fig. 5. In Fig. 6, I have shown diagrammatically a series of wavers applied to 40 the left side of the head, and it will be noted that this lateral movement of the bar 7 produces an inclined or irregular shaped wave, wherein the distance from the base of the wave adjacent the side member 2 to the 45 crest thereof, is slightly greater than the distance from the base portion of the wave at the side member 1 from said crest. This inclines the wave downwardly, or produces a slightly irregular wave, which is less precise, and hence more graceful and desirable. 50 It will readily be seen that the waver may be used at either side of the head with the point of the bar inserted beneath the strand of hair, and the bar will be shifted to one side or the other so as to incline the wave downwardly away from the crown of the head. It is understood, of course, that in using my device, the hair is first dampened 55 in the usual way, and then the waver is applied, and it should remain holding the hair in waved form until it dries. It is often desired to apply the wavers to the hair and allow them to remain there overnight. This 60 can be readily done without any discomfort to the wearer, for the reason that the bar 7,

when moved laterally, is moved to a point entirely at one side of the side members, and therefore, the central portion can be readily flexed or bent close to the head of the wearer. Then again, the wave which is formed by 70 my improved waver, can be made of the size desired without having the bar project through the body portion of the waver to an undesirable extent, as the wave is lengthened by the lateral movement of the bar. 75

While I have shown and described my improved waver as particularly useful for water waving, it is, of course, understood that it may be used in other types of hair waving. The lateral movement of the members relative to each other would be particularly useful in hair waving wherein heat is applied for the forming of the waves, for the reason that the wave can be inclined or made of irregular form, and therefore, the 80 invention is not limited to the details of construction or the operation described. It is further obvious that the details of construction can be readily varied without departing from the spirit of the invention as 85 set forth in the appended claims.

Having thus described the invention, what I claim as new and desire to secure by Letters-Patent, is—

1. A hair waver comprising a body portion shaped to provide a slot longitudinally thereof through which the hair may be crimped to form a wave, a bar attached to said body portion and movable through said slot for forming and maintaining the wave, and means for connecting said bar to the body portion so that said bar after passing through the slot may be moved laterally to one side of said slot. 95

2. A hair waver comprising a body portion shaped to provide a slot longitudinally thereof through which the hair may be crimped to form a wave, a bar attached to said body portion and movable through said slot for forming and maintaining the wave, and means for connecting said bar to the body portion so that said bar after passing through the slot may be moved laterally to one side of said slot, said body portion being provided with integral means for holding 100 the bar in its laterally shifted positions. 110

3. A hair waver comprising a body portion having spaced side members with connected loop portions at the opposite ends thereof, a bar pivoted to one of said loop portions and adapted to pass between said side members for crimping the hair to form a wave therein, said bar being shiftable laterally of the loop portions for increasing the size of the wave and inclining the same, said side members having means for maintaining the bar in its laterally shifted positions. 115

4. A hair waver comprising a body portion having spaced side members with con- 120

nnected loop portions at the opposite ends thereof, a bar pivoted to one of said loop portions and adapted to pass between said side members for crimping the hair to form a wave therein, said bar being shiftable laterally of the loop portions for increasing the size of the wave and inclining the same, said side members at the ends thereof adjacent the loop portions having raised shoulders over which the bar may be forced and serving to hold the bar in its laterally shifted position.

In testimony whereof, I affix my signature.

BESSIE E. HAYNES.
